UNITED STATES PATENT OFFICE.

WILLIAM D. HENDERSON, OF CHICAGO, ILLINOIS, ASSIGNOR TO THE WHITEHEAD & HOAG COMPANY, OF NEWARK, NEW JERSEY, A CORPORATION OF NEW JERSEY.

CULINARY SUPPLY-CARD.

No. 888,708.

Specification of Letters Patent.

Patented May 26, 1908.

Application filed July 17, 1906. Serial No. 326,638.

To all whom it may concern:

Be it known that I, WILLIAM D. HENDERSON, of Chicago, in the county of Cook, in the State of Illinois, have invented new and useful Improvements in Culinary Supply-Cards, of which the following, taken in connection with the accompanying drawings, is a full, clear, and exact description.

This invention relates to improvements in 10 culinary supply-cards commonly known as kitchen-reminders adapted to be kept in the kitchen or culinary department to indicate at a glance the absence of any culinary supplies.

15 My object, therefore, is to provide a simple, comparatively inexpensive device by which the cook or other attendant may indicate the absence of any, or necessity for culinary supplies as they may become exhausted 20 so that the grocery-order may be taken directly from such device without personal investigation of the supplies.

In other words, I have sought to combine 25 in one device, a kitchen-reminder and an advertising medium, upon which is printed the various articles usually used in cooking, and with which, is associated a series of movable members adapted to be brought into registration with any one of said articles to remind 30 the cook that such article is exhausted or needed from the grocery, so that any one examining the device, can readily tell at a glance just what articles are needed.

In the drawings—Figure 1 is a perspective 35 view of my improved kitchen-reminder. Fig. 2 is a transverse sectional view through the card seen in Fig. 1 at the point where the strings are fastened. Fig. 3 is a similar sectional view showing a modified means for 40 fastening the cores to the card.

My improved kitchen-reminder consists of a card —1 of any suitable material, such as card-board, or any pyroxylin material.

The longitudinal edges of this card are 45 formed with a series of notches or slits —2—, which are preferably V-shape for receiving any one of a series of movable flexible members, as cords or strings —3—, which are attached in any desired manner to any part of 50 the card, or may be entirely separate from the card, and simply bunched or tied together to leave their ends free to be drawn into the slits —2—.

One or both of the flat surfaces of the card 55 are provided with printed names of the arti-

cles which are usually used for the table in cooking. These names are printed in line with the notches or slits —2—, one for each slit. The cords or strings —3— are preferably attached to the card leaving their ends 60 free to be drawn into one end of the notches at either side of the card opposite to the name of the article which may be needed, so that when the cook finds that a certain article is becoming exhausted, he or she may 65 draw one of the strings through the notch opposite such article, thereby indicating at a glance that this article is needed. In this way, several of the strings may be drawn through as many notches during a given 70 period or interval of time, as one day, so that when the groceryman calls for an order it may be taken directly from the card, as indicated by the position of the strings.

In Figs. 1 and 2, the strings —3— are 75 shown as knotted at —6— at their longitudinal centers, leaving the ends free, the knot —6— being passed through an aperture —6'— in the card —1— where the knot at the back of the card is somewhat larger than 80 the opening to retain the strings in place.

In Fig. 3, I have shown the cords —3— as having their longitudinal centers clasped in a loop or staple —7— which is passed through the aperture —6'— and has its ends bent 85 laterally upon the back of the card —1— to retain the strings in place.

While I have described this invention as applicable to a kitchen reminder, yet I do not desire to limit myself to such use, as it will 90 be evident that the device may be used for a reminder of any kind, or for any use, and may be used for lists, such as telephone lists, and the like in which numerals are used to indicate names and things.

95 What I claim is:

1. A culinary supply-card having a series of slits and the names of the articles printed on the card, each in line with one of the slits, and movable members fastened to the card 100 at the same point each having a portion thereof adapted to be drawn into one of the slits.

2. A kitchen-reminder consisting of a plate having printed thereon the names of 105 the articles which may be needed, in combination with a series of flexible members fastened to the card substantially midway between its edges and each movable into alignment with any one of the printed ar- 110

ticles, and means on the card for holding the flexible members in their adjusted positions.

3. A kitchen-reminder consisting of a plate having printed thereon the names of the articles needed and provided with a series of slits, one for each name, in combination with a series of flexible members attached substantially midway between their ends, to the card, and having their free ends movable into and out of the slits.

4. A kitchen-reminder comprising a card having printed thereon the names of the articles needed, said card having each of its longitudinal edges formed with slits, and strings having their central portions attached

to the card, and their free ends adapted to be drawn into said slits.

5. A culinary supply card consisting of a plate having its opposite longitudinal edges provided with V-shape notches, in combination with a series of strings fastened substantially midway between its longitudinal edges. 20

In witness whereof I have hereunto set my hand this third day of July, 1906.

WILLIAM D. HENDERSON.
